MOSES SOLOMON OKUN, OF NEW YORK, N. Y., ASSIGNOR OF ONE-THIRD TO GLEN E. SMITH, OF CHICAGO, ILLINOIS.

ELECTRIC LAMP.

1,214,816.

Specification of Letters Patent.

Patented Feb. 6, 1917.

Application filed January 26, 1912, Serial No. 673,684. Renewed June 22, 1916. Serial No. 105,292.

To all whom it may concern:

Be it known that I, MOSES S. OKUN, citizen of the United States, and resident of New York city, in the county of New York and State of New York, have invented certain new and useful Improved Electric Lamps, of which the following is a specification.

The object of my invention is to construct a simple, cheap and efficient electric lamp in which a great percentage of electric energy is transferred into light.

My invention relates to such types of electric lamps in which the light is produced by passing an electric current through a weak contact between two or more electrodes, touching one another at a slight pressure. These lamps are commonly called semi-incandescent lamps.

In my invention I provide means to prevent the fusion or the sticking of the electrodes to one another, such sticking of the electrodes is the result of the excessive heat developed at the point of contact. The fusion or the sticking of the electrodes reduces considerably the electrical resistance of said contact and interferes with the successful operation of the lamp.

I also provide means whereby the electric current heats the points of both electrodes to such degree as to produce light by the points or the end of both of them. In order to attain such results, I make both electrodes of such cross-sectional area as to permit a great concentration of heat at their point of contact, so as to heat up the points of both electrodes substantially to the same degree. I also make both of the electrodes of substantially the same cross-sectional area. I also employ a magnet or a solenoid to regulate automatically the pressure between the electrodes and to prevent the fusion or the sticking of the electrodes to one another. I also provide means to retard the consumption of the electrodes and to prolong the life of the same as much as possible. For this purpose I place the electrodes or the ends of the electrodes in a vacuum or in an inclosure into which the outside air has a very difficult access.

I have illustrated my invention in the accompanying drawings, where—

Figures 1, 2, 3 and 4 represent vertical sectional views of different modifications of my invention.

Referring to Fig. 1, ordinals 1 and 2 represent the electrodes of my lamp, which are both preferably made of substantially the same cross-sectional area. These electrodes are made of carbon, titanium, tungsten, vanadium or of any other material having a high melting point.

The electrodes 1 and 2 are placed in the inclosed globe 3 which is pressed by the spring 5 against the cover 4. If necessary the globe 3 can be cemented to the cover 4, so as to secure an absolutely air tight connection between them. The electrode 2 is fastened to the metallic rod 13, while the electrode 1 is carried by the iron core 6, which slides in the tube 8 and which is operated by the magnetic device 7. In the embodiment chosen for illustration, the magnetic device is a solenoid 7. The tube 8 is closed air tight by the cap 14 and is provided with an air tight valve 15 through which the air of the globe 3 can be pumped out. The winding of the solenoid 7 is placed in series with the electrodes of the lamp, and is connected with the binding posts 9 and 11, which are connected with the line.

The current passes through the binding post 11 (which is insulated by the insulating material 12 from the cover 4), electrodes 1 and 2, rod 13, binding post 10 (which is also insulated by the insulating material 12 from the cover 4) solenoid 7 and binding post 9.

When the air is pumped out from the globe 3 the valve 15 is closed, so that no air can get into the globe.

This lamp can be used with an alternating or continuous current, also in series or in multiple. The voltage and amperage used in my lamp, can be varied to fit the conditions for which the lamp is constructed. The object of the solenoid 7 is to regulate the current passing through the lamp. Suppose the lamp is constructed for 10 amperes; when the current is turned on, the weight of the iron core establishes a good electrical connection between the electrodes 1 and 2, causing a stronger current than 10 amperes to pass through the lamp and through the solenoid 7; this increases the action of the solenoid 7 upon the core 6; as a result of it the pressure between the electrodes 1 and 2 is reduced; this increases the electrical resistance of the contact between them and reduces the current to its normal strength of 10 amperes.

Fig. 2 represents another modification of my invention. In this modification, the winding of the solenoid 7 is of greater electrical resistance for the reason that it is made of fine wire. This winding of the solenoid 7 is placed in multiple or in shunt with the electrodes 1 and 2 and not in series as in the lamp shown in Fig. 1. The solenoid 7 in Fig. 2 regulates the voltage of the lamp and not the current as in Fig. 1. This form of lamp is particularly adapted for use in series on lines of constant current. When not in operation the electrodes 1 and 2 are separated by the spring 21, which acts upon the core 6. The winding of the solenoid 7 is connected with the binding posts 19 and 20; the binding posts 19 and 20 are also connected with the line. The binding post 19 is also connected with the electrode 1 while the binding post 20 is connected with the electrode 2. When the current is turned on, the solenoid 7 acting upon the core 6 (which reacts upon the spring 21) brings in contact the electrodes 1 and 2, causing an electric current to pass through them. When the pressure between the electrodes 1 and 2 is too great, the voltage of the lamp decreases, reducing the current in the shunt winding of the solenoid 7 and also the action of the solenoid 7 upon the core 6; the spring 21 acting upon the core 6 reduces the pressure and increases the resistance between the electrodes, thus bringing the lamp to its normal voltage.

Fig. 3 represents another modification of my invention. In this modification the globe 3 which is of cylindrical form is placed above the solenoid 7. The core 6 with the lower electrode 2 fastened to it, is pressed by the spring 10 against the upper electrode 1. The globe 3 is open at both ends and is provided with covers 4 and 14, which preferably are cemented to the globe 3. The solenoid 7 is placed in series with the electrodes 1 and 2. The line is connected with the conductors 17 and 18. The current passes through the conductor 18, metallic cover 14, electrodes 1 and 2, iron core 6, conductors 12 and 13, solenoid winding 7, and conductor 17. When the current in the lamp is too strong the solenoid 7 acting upon the spring 10 reduces the pressure and increases the electrical resistance between the electrodes, bringing the current to its normal strength.

Fig. 4 shows a modified form of the globe 3. This globe which is open at both ends is provided with two cylindrical extensions 11 and 12 and it is closed with the covers 9 and 14 which may be (if necessary) cemented to the same. The solenoid is in series with the electrodes 1 and 2; the core 6 with the electrode 2 fastened to it is pressed against the electrode 1 by the spring 13. The electrode 1 is fastened to the cover 14, which is provided with the air tight valve 15, through

which the air of the globe can be pumped out. The line is connected with the binding posts 16 and 19. The current passes through the binding post 19, cover 14, electrodes 1 and 2, iron core 6, spring 13, cover 9, spring 24, conductor 25, solenoid 7, conductor 17, and binding post 16. The operation of this lamp is the same as that of the lamp shown in Figs. 1 and 3.

My invention can be operated successfully without pumping out the air from the globe, as the globe in my lamp is tightly closed and no outside air can enter into the same. The free oxygen contained in the globe will be consumed quickly and the further consumption of the electrodes will be discontinued. When the points of the electrodes are burned or used up the iron core slides down (as in Figs. 1 and 2) or is pressed up by the spring (as in Figs. 3 and 4) and establishes again an electrical connection between the electrodes 1 and 2. Instead of using a solenoid for the magnetic device for the purpose of regulating the pressure between the electrodes, a regular magnet could be employed.

My improved electric lamp may be used wherever apparatus of this class is desired, the apparatus shown and described in the specification is merely illustrative, and changes in and modifications of the construction herein described, may be made within the scope of the appended claims, without departing from the spirit of my invention or sacrificing its advantages.

I claim—

1. An electric lamp having electrodes, means for engaging the electrodes in contact under slight pressure during the operation of the lamp and means to regulate automatically the electrical resistance of said contact, so as to maintain the current and the voltage of the lamp approximately constant, substantially as described.

2. An electric lamp having electrodes, means for engaging the electrodes in contact under slight pressure during the operation of the lamp and means operated by the electric current, passing through the lamp for regulating the electrical resistance of said contact, so as to maintain the current and the voltage of the said lamp approximately constant, substantially as described.

3. An electric lamp having electrodes in contact under slight pressure during the operation of the lamp, an electromagnetic device associated with the electrodes and a circuit passing through said electrodes and said electromagnetic device for regulating the pressure of said contact, so as to maintain the current and the voltage of the lamp approximately constant, substantially as described.

4. An electric lamp having electrodes, means for engaging the electrodes in contact

- under slight pressure during the operation of the lamp, means to separate the said electrodes when the current is not passing through the lamp and means operated by the electric current for regulating the pressure of the contact of the electrodes, substantially as described.
5. An electric lamp having electrodes, means for engaging the electrodes in contact under slight pressure during the operation of the lamp, means to regulate automatically the electrical resistance of said contact, so as to maintain the current and the voltage of the lamp approximately constant, an inclosure from which the air is exhausted and into which said electrodes are placed in order to retard the consumption of the same, substantially as described.
6. An electric lamp having electrodes, means for engaging the electrodes under slight pressure during the operation of the lamp, an electromagnetic device to regulate the electrical resistance of said contact, so as to maintain the current and voltage of the lamp approximately constant, an inclosure from which the air is exhausted and into which said electrodes are placed in
- 10
- 15
- 20
- 25

order to retard the consumption of the same, substantially as described.

7. An electric lamp, having electrodes, means for engaging the electrodes in contact under slight pressure during the operation of the lamp and means operated by the electric current passing through the lamp to prevent the sticking or fusion of the electrodes to one another, substantially as described.

8. An electric lamp having electrodes, means for engaging the electrodes in contact under slight pressure during the operation of the lamp, an electromagnetic device for the purpose of preventing the fusion or the sticking of the electrodes one to another, an inclosure from which the air is exhausted and into which said electrodes are placed in order to retard the consumption of the same, substantially as described.

Signed at the city of New York in the county of New York and State of New York this 25th day of January A. D. 1912.

MOSES SOLOMON OKUN.
